FRANK ACHILLE BIENVENU, OF MONTREAL, QUEBEC, CANADA, ASSIGNOR, BY MESNE ASSIGNMENTS, TO CATELLI MACARONI PRODUCTS CORPORATION LIMITED, OF MONTREAL, CANADA

CAN-HEATING DEVICE

Application filed July 30, 1927. Serial No. 209,548.

The invention relates to a can heating device, as described in the present specification and illustrated in the accompanying drawings that form part of the same.

The invention consists essentially of the 5 novel features of construction pointed out in the claim for novelty following a description containing an explanation in detail of an acceptable form of the invention.

The objects of the invention are to re- 10 store heat to canned foods in a certain stage in the process of preparing the foods for preservation; to facilitate the passage of the cans and thereby avoid delay and any diminution of the output; to maintain the flavor 15 of the packed foods; to carry out these measures at the least possible expense to the canners; and generally to provide a machine that will be of material assistance in preserving foods for transport and storage 20 and at the same time economize in so far as the expenditures for labor and the generation of heat are concerned.

In the drawings, Figure 1 is a longitudinal sectional view of the machine.

25 Figure 2 is a cross sectional view on the line 2—2 in Figure 1 showing the feed end.

Figure 3 is a perspective detail of the shower member.

Figure 4 is a perspective detail of the 30 draining table.

Like numerals of reference indicate corresponding parts in the various figures.

Referring to the drawings, the standing frame 10 forms a support for the box 11 35 from which the legs 12 extend to said standing frame and to which they are adjustably secured.

The box 11 contains the inclined angle iron tracks 13 and 14 supported in the de- 40 sired positions on the brackets 15 and 16 which are rigidly secured in the interior of the box in pairs and slotted at 17 for the pins 18 that hold the tracks to their adjusted position according to the sizes of the can 45 passing therewith.

The shower member 19 is formed of a pipe 20 formed in substantially U-shape and having an inlet pipe 21 from the closed end of 50 the U connected to a steam supply pipe 22

having the valve 23 introduced therein and extending to a steam plant.

One leg of the U is inwardly turned at the extremity and forms the steam nozzle 24 adapted to spurt steam on the cans rolling along the tracks 13 and 14. Another nozzle 55 25 projects below the tracks and spouts upwardly. There are two more of these lower nozzles 26 and 27 and two more overhead nozzles 28 and 29 as well as two side nozzles 60 30 and 31, thus there are steam jets completely surrounding the cans and therefore the cans rolling down the tracks are bound to be liberally showered with steam, which condenses and is drained from the box.

The shower member is held at one end 65 by the bracket 32 from the tracks and at the other end by the steam supply pipe 20.

The chute 33 is at the elevated end of the inclined tracks and leads thereto from the heading machine, so that when the cans 70 leave the latter, they slide down the chute on to the tracks where they roll by gravity under, over and beside the jets of steam, thereby becoming thoroughly heated after the temperature has fallen during the operations of filling and heading.

The cans roll on to the delivery and draining table 34, where the condensed steam in the form of water drains to the central holes 35, from which it flows to the spout 36. 80 The table 34 is also adjustable as to height and is supported in the standing frame 37 permanently resting on the floor.

This machine is preferably used as a step in a canning process, though it may be more 85 generally used.

In this process of baking and canning pork and beans after the pots leave the oven they are emptied into a bowl, the food has a chance to drop in temperature a little before 90 the cans are filled and closed, however this is more beneficial than otherwise, still to maintain the flavor and insure absorption it is advisable to heat again before sterilization and this heating may be done as described by steam or by slight changes by electricity or gas.

It is most essential to provide a receptacle that will not cook the beans, as that has been done already in the oven, but in the 100

filling process the temperature has gone down and they are not in proper condition for sterilization because of that drop therefore a space is furnished where a spray merely restores temperature practically in the open air as the shield 38 on the top is merely a deflector partially closing in the box.

What I claim is:—

- 10 A can heating device comprising a box having an opening through the top at the inlet end, and an outlet at the other end, hangers formed of slotted bars and adjustable transverse rails, a can trackway supported on said rails at a chosen level and inclined, a steam feed pipe connected to a suitable source, a spray member having transverse, parallel, longitudinal and vertical pipes carrying nozzles directed upwardly, downwardly and sideways and adjustably mounted and supported by said steam feed pipe, and a draining table at said outlet from said box.
